(57) **CLAIM**

The ornamental design for a tilt helm for a boat steering wheel, as shown and described.

DESCRIPTION

FIG. 1 is a perspective view of the tilt helm for a boat steering wheel showing my new design.

FIG. 2 is a front elevation view of FIG. 1.

FIG. 3 is a top plan view of FIG. 1.

FIG. 4 is a bottom plan view of FIG. 1.

FIG. 5 is a right side elevation view of FIG. 1; and, FIG. 6 is a left side elevation view of FIG. 1.

The broken lines immediately adjacent the shaded areas represent the bounds of the claim and all other broken lines are for illustrative purposes only. None of the broken lines form a part of the claimed design.
